UNITED STATES PATENT OFFICE

120,117

DESIGN FOR A BOWLING ALLEY

Edward J. Collins, Los Angeles, Calif., assignor to R. W. Hood, Chicago, Ill.

Application January 29, 1940, Serial No. 89,845

Term of patent 7 years

To all whom it may concern:

Be it known that I, Edward J. Collins, a citizen of the United States and a resident of Los Angeles, in the county of Los Angeles and State of California, have invented a new, original, and ornamental Design for a Bowling Alley, of which the following is a specification, reference being had to the accompanying drawing, forming a part thereof, and in which:

Fig. 1 is a top plan view of a bowling alley showing my new design;

Fig. 2 is a perspective view of that portion of the bowling alley to the left of lines 2—2 in Fig. 1 on a slightly larger scale; and

Fig. 3 is a perspective view of that portion of the bowling alley to the right of lines 3—3 in Fig. 1 on a slightly larger scale.

I claim:

The ornamental design for a bowling alley, as shown.

EDWARD J. COLLINS.
